UNITED STATES PATENT OFFICE

JOHN L. MOHUN, OF OMAHA, NEBRASKA

STEAM ENGINE

Application filed August 9, 1924. Serial No. 731,053.

This invention relates to improvements in steam engines.

An object of the invention is to provide a device for use in connection with the cylinders of a steam engine, such as a locomotive, including cocks or valves for draining or venting the liquid of condensation from the cylinders of the engine.

Another object of the invention is to provide a device having means which positively and at all times hold the venting means in venting or open position while the locomotive is at rest, together with means for automatically closing said venting means by utilizing a portion of the steam admitted to the locomotive cylinders for driving the same.

Another object of the invention is to provide automatic venting means of this character which are arranged to close when the locomotive is drifting with the steam power shut off from the cylinders.

Still another object of the invention is to provide venting means of this character, together with means for operating said venting means to open the same during the working operation of the locomotive cylinders, such means being operated from a point convenient to the engineman.

Other objects of the invention will more clearly and fully appear from the description and claims hereinafter following.

In the drawings forming a part of this specification, Figure 1 is a fragmentary, broken, side elevation of a locomotive, showing my invention in connection therewith. Figure 2 is an enlarged, fragmentary, transverse, sectional view of the invention taken substantially on the line 2-2 of Figure 1. Figure 3 is a transverse, sectional view of a three-way valve arrangement used in connection with my invention. Figure 4 is an enlarged, top plan view of the valve or cock used in connection with my invention. Figure 5 is an enlarged, vertical, sectional view of the valve or cock used in connection with my invention, showing the valve in fully opened position, together with a portion of the actuating mechanism thereof. Figure 6 is a vertical, sectional view of the valve similar to Figure 5, showing one of the

closed positions of the valve. Figure 7 is a vertical, sectional view of the valve, similar to Figures 5 and 6, showing another closed position of the valve. Figure 8 is a broken side elevational view of a locomotive showing a somewhat different embodiment of the invention in connection therewith. And Figure 9 is an enlarged, fragmentary, transverse, sectional view similar to Figure 2, showing the construction illustrated in connection with the embodiment of the invention as disclosed in Figure 8.

Referring more particularly to the drawings, 10 represents a fragment of a locomotive, having the usual steam cylinder 11, and the steam pipe 12 communicating with such cylinder for admitting the steam thereto.

My invention includes broadly, similar cylinder cocks or valves A, disposed adjacent the ends of the locomotive cylinder 11; a mechanism indicated generally at B for operating such valves; an auxiliary steam cylinder C for actuating the mechanism B; a three-way valve D; a steam pipe E communicating with the three-way valve D and the cylinder C; and a pipe F communicating with the inlet pipe 12 of the cylinder 11 and the valve D.

The cocks or valves A are identical in form, and only one of the same is shown and described in detail; it should be understood, however, that I preferably provide two cocks or valves for each cylinder of the locomotive. Each valve or cock A preferably comprises a nipple 20 adapted to be threaded into the cylinder 11, and such nipple is provided with a frusto-conical valve seat 21, and an enlarged portion 22, adapted to be threaded upon the body portion 23 of a valve casing 24. The casing 24 of the valve is preferably provided with an inverted frusto-conical seat 25, oppositely disposed with reference to, and spaced a suitable distance from, the seat 21, thereby providing the intermediate chamber 26, as shown in Figures 5 to 7, inclusive, the chamber 26 being adapted to loosely contain a hollow ball valve 27 disposed therein. The casing 24 is also preferably provided with a laterally disposed outlet duct 28, communicating with the chamber 26, as clearly

shown in the drawings. The casing 24 is also preferably provided with a vertically disposed bore 29 at its lower end, which is adapted to slidably receive a pin 30, which extends a suitable distance into the casing, the pin preferably having an enlarged head 31 formed thereon, the arrangement being such that the ball 27 normally rests upon the seat 25 through the influence of gravity until it is raised from such seat by movement of the pin 30.

Mechanism is provided for actuating the valve 27 through the medium of the pin 30, and such mechanism preferably includes fingers 32, the inner end 33 of each of which is arranged to bear against the head 31 of the pin 30. The fingers 32 are preferably mounted for operation by means of projecting ears 34 formed on the valve casings A, the fingers 32 being disposed between such ears, and preferably rigidly mounted upon a shaft 35, the ends of such shaft extending through the ears 34, so that oscillation of the shaft will impart movement to each finger 32 mounted thereon to raise and lower the pin 30, and the ball valve 27, of the related cock A.

The shaft 35, preferably midway between its ends, has mounted thereon a crank arm 36 through which the shaft and the fingers 32 may be operated. Such crank arm 36 is preferably pivotally connected, as shown at 37, to a link 38, the outer end of such link extending into the small auxiliary steam cylinder C, mounted by any suitable means adjacent the locomotive steam cylinder 11.

The auxiliary steam cylinder C is preferably provided with inner and outer chambers 39 and 40, such chambers being defined by a partition 41, having an opening 41' therein, as shown, and by the outer and inner end walls 42 and 43 respectively. The inner end portion of the cylinder C is preferably tapered as shown, and the inner wall thereof is provided with a slot 44 permitting entrance of the related end of the link 38. A piston 45, preferably cup-shaped in form, as shown, is slidably disposed in the chamber 39, the sliding movement of such piston being limited by the outer wall 42, and partition 41. The piston 45 is pivotally connected, as shown at 46, with the outer end of the link 38, for reciprocating the same, the slot 44 serving to accommodate the lateral movement of the link 38. Mounted in the chamber 40 is a spring 47, the outer end of which is adapted to bear against the end wall 43 of the cylinder C, such spring 47 preferably being disposed about the link 38, the inner end thereof being arranged to bear against a collar 48 mounted on the link 38, such spring during a portion of the operation of the parts also extending partially into the chamber 39 of the cylinder C, as shown. The spring serves to normally urge each finger 32 into engagement

with the pin 30 of each valve A so as to hold the ball 27 off the seat 25.

The cylinder C is preferably connected by means of the steam pipe E with the three-way valve D, and the steam pipe F connects the valve D, with the steam pipe 12 of the cylinder 11. The valve D may be of any desired construction, preferably including a casing having openings 49, 50 and 51 therein, and a valve 52 rotatably mounted in the casing, such valve being provided with an angular passage 53 therein, terminating in the openings 54 and 55, which are adapted to register with the openings 49 and 50 in one position of the valve, and with the openings 50 and 51 in another position of the valve. A handle 56 is provided for operating the valve stem 52. The valve D is preferably disposed in a position in the cab of the locomotive where it may be conveniently operated by the engineman.

In operation, when the locomotive is at rest, and no steam is being admitted to the steam pipe 12, the spring 47 in the cylinder 39 acts to normally hold the piston 45 to its outermost position, as clearly shown in Figure 2. This operation, through the link 38 and the crank arm 36, imparts an inward movement to the fingers 32, each bearing against the head 31 of the pin 30, to raise the ball valve 27 into open position, that is, in a position off of the seat 25. When the parts are in this position, the ball valve is positively held open by the spring, so that the liquid of condensation in the locomotive cylinder 11 is free to pass out of the port 28.

When the locomotive is started and is working, steam is admitted into the cylinder 11 through the pipe 12 and through the pipe F which communicates directly with the steam pipe 12, the three-way valve D, and the pipe E, which communicates directly with the auxiliary cylinder C, the steam pressure automatically forcing the piston 45 inwardly, which causes the retraction of each finger 32 from engagement with the pin 30, thereby permitting the dropping of this pin through gravity, and also through the action of steam pressure upon the ball 27, such steam pressure also serving to hold the ball 27 tightly in engagement with the seat 25, during the working operation of the cylinder 11. During drifting of the locomotive, that is, when the same is moving and the steam is cut off from the cylinder 12, the movement of the piston creates a partial vacuum, or in other words, a change in pressure is produced, which effects a lifting of the ball 27 into engagement with the seat 21 of the valve, so as to close the valve and effectually prevent entrance of relatively cold air and foreign matter into the cylinder 11.

When it is desired to operate the valve 27 to vent the condensation from the locomotive cylinder during working operation of the

same, the valve D may be operated by the enginemen to close the inlet of the pipe F thereto, this being accomplished by oscillating the handle 56 of the valve 52, so as to bring the opening 54 of the angular duct 53 out of communication with the pipe F and into communication with the opening 50 and the pipe E, this movement serving to cause the opposite opening 55 of the duct 53 to register with the exhaust opening 51 in the valve casing 54. This movement of the valve D serves to exhaust the steam in the auxiliary cylinder C and pipe E, so that the spring 47 is free to return the piston 45 to its outermost position, this action, through the related connections, serving to cause the finger 32 of each cock A to raise the valve 27 off of the seat 25, thereby permitting venting of the liquid of condensation.

The embodiment of the invention illustrated in Figure 8 of the drawings, contemplates the use of an auxiliary cylinder and its associated mechanism for actuating the venting means, which cylinder serves the same purpose as the auxiliary cylinder C in the combination, though the construction of such cylinder and its piston is such as to afford means for operating the venting means, including elements which coact through the production of a differential steam pressure. Referring to Figure 8, the main steam cylinder is indicated by the numeral 111, and the auxiliary cylinder by the letter G. The cylinder G preferably has a main body portion 112, and a reduced portion 113, which in conjunction with the closures 114 and 115 provide a relatively large, steam-tight compartment 116, and a smaller, steam-tight compartment 117. Communicating with the compartment 116 is a steam pipe 118, which leads to a three-way valve of a type shown at D in the other figures of the drawing, and thence to the steam pipe 12, in the same manner as the steam pipes E and F, hereinbefore described. Communicating with the compartment 117 is a somewhat smaller steam pipe 119, which leads to and is in communication with the steam dome (not shown) of the locomotive as ordinarily provided. Mounted for reciprocatory movement in the cylinder G is a piston which preferably comprises a cup-shaped member 120 adapted for snug sliding engagement with the inner walls of the portion 112 of the cylinder, such piston having a reduced extension 121 adapted to have a snug sliding fit with the inner walls of the portion 113 of the cylinder, as shown, there preferably being a cavity 122 in the extension 121, such cavity communicating with the cavity 123 provided by the walls of the cup-shaped portion 120 of the piston, the arrangement being such that the disposition of the parts of the piston serves to seal the compartments 116 and 117 one from the other. Connected to the outer end of the extension

121 and extending externally of the cylinder is a piston rod 124, a gland 125 being provided to afford a tight connection while permitting reciprocation of said rod with the piston. The rod 124 has its outer end pivotally connected to a link 126, a fragment of which is shown in Figure 8, such link being adapted to be connected to the crank 36 in the same manner as the link 38, reciprocation of the link 126 actuating venting mechanism of the character hereinbefore described. By this arrangement, when no steam is being admitted to the compartment 116, as when the engine is at rest, or because of the operation of the three-way valve when the engine is working, steam is constantly admitted to the compartment 117 by the pipe 119, which communicates with the steam dome of the engine so that the piston is normally held in retracted position, thereby normally positively holding the venting means in open position. When the locomotive is started and is working, steam is admitted into the larger compartment 116 and by reason of the greater area acted upon by the same, the resistance offered by the pressure in the smaller compartment 117 is overcome, resulting in an outward movement of the link 126, permitting closing of the venting means. In other words, the auxiliary cylinder and its contained mechanism include means for effecting a differential in steam pressure resistance which serves to automatically operate the venting means.

I have herein shown and described what I now consider the preferred manner of carrying out my invention, but the same is merely illustrative and I contemplate all changes and modifications that come within the scope of the claims appended hereto.

I claim:

1. In a steam engine, the combination with a cylinder having means providing a steam inlet; a valve connected with said cylinder; and urged to closed position by pressure in said cylinder; means for operating said valve, said means being adapted to normally hold said valve in open position; an auxiliary steam cylinder cooperating with said first steam cylinder, said auxiliary cylinder including a piston connected with said valve operating means; means connected to the inlet of said first cylinder for admitting steam to said auxiliary cylinder; and a three-way valve interposed in the steam line to said auxiliary steam cylinder.

2. In a steam engine, the combination with a cylinder having a steam inlet; a plurality of venting means for said cylinder normally urged to closed position; mechanism for holding the venting means open; and means for simultaneously operating said venting means, said means including an auxiliary steam cylinder, including a piston, adapted to receive steam from the inlet of said first cyl-

inder simultaneously with admission of steam to said first cylinder to actuate said operating means to permit closing of said venting means, the piston of said auxiliary cylinder being connected to said operating means.

3. In a steam engine, the combination with a cylinder having a steam inlet and a piston; of a plurality of valves communicating with said main cylinder, each of said valves including spaced seats and a ball valve; an operating shaft connected to said valves and having arms thereon for operating the balls of said valves; a crank on said shaft; an auxiliary steam cylinder having a link connected at one end to said crank and at its opposite end to the piston in said cylinder; resilient means normally holding said link in retracted position; and a steam pipe connected with said auxiliary steam cylinder and the inlet to said first cylinder.

4. In a steam engine, the combination with a cylinder having a steam inlet and a piston; of a plurality of valves communicating with said cylinder, each of said valves including oppositely disposed, spaced seats and a ball valve; an operating shaft connected to said valves and having arms thereon for operating the balls of said valves; a crank on said shaft; an auxiliary steam cylinder having a link connected at one end to said crank and at its opposite end to the piston in said cylinder; resilient means normally holding said link in retracted position; a steam pipe connected with said auxiliary steam cylinder and the inlet to said first cylinder; and a three-way valve interposed in said steam pipe.

5. In a steam engine including in combination a cylinder valve means for venting condensation from said cylinder including opposed valve seats and a ball valve; means arranged to normally positively retain said valve in venting position, and means operated by steam pressure for releasing said ball valve from venting position.

6. In a steam engine, the combination with a cylinder and piston; of venting means for said cylinder including valve means having opposed valve seats communicating with said cylinder; and a valve adapted to engage one or the other of said seats at different times, dependent upon variation of pressure in the cylinder; means for normally holding said valve in venting position when the engine is at rest; and mechanism communicating with said cylinder and operable by the admission of steam thereto to withdraw said holding means from said valve when the engine is working.

7. In a steam engine, including in combination a main cylinder and its associated piston, a steam supply and a steam inlet to said cylinder; valve means for venting said cylinder, said valve means being urged to closed position when steam pressure exists in said cylinder; means for operating said valve means,

including an auxiliary cylinder having a relatively large compartment communicating with said steam inlet and a smaller compartment connected with the steam supply independently of said cylinder inlet; and a piston having portions correspondingly large and small and co-operating with said compartments, said piston being connected with said valve means for operating the same to effect opening or permit closing thereof.

8. In a steam engine, the combination with a main cylinder and piston; of a steam supply for said main cylinder; valve means for venting condensation from said main cylinder, said valve means being urged toward closed position directly under the influence of the pressure of steam admitted to said main cylinder; operating means adapted normally to hold said valve means open at all times; and mechanism communicating with said steam supply and operated by pressure of said steam for withdrawing said operating means to permit said valve means to assume closed position.

9. In a steam engine, the combination with a cylinder and piston; of a steam supply connected with said cylinder; valve means for venting condensation from said cylinder, said valve means being urged toward closed position by steam pressure within the cylinder while the latter is operating; valve actuating means normally preventing closing of said valve means, and adapted to be connected with said steam supply simultaneously with the admission of steam to said main cylinder to effect withdrawal of said actuating means to permit said valve means to close; and manually controlled mechanism for said actuating means for effecting operation of the same to vent said valve means against the steam pressure in said cylinder when the same is operating.

10. In a steam engine, the combination with a cylinder having a steam inlet; a valve connected with said cylinder, said valve being urged toward closed position by pressure of steam admitted to said cylinder; means for operating said valve, said means being adapted in one position to hold said valve open and being movable to position to permit said valve to close; an auxiliary steam cylinder co-operating with said main steam cylinder, said auxiliary cylinder including a piston connected with said valve operating means, said piston being normally urged to move said operating means in one direction to hold the valve open; conducting means connected to the inlet of said first cylinder for admitting steam to said auxiliary cylinder simultaneously with the admission of steam to said first cylinder to operate said piston in the opposite direction and permit closing of said valve; and means for cutting off the admission of steam to said auxiliary cylinder and

exhausting said steam therefrom to permit said piston to resume its normal position.

11. In a steam engine, the combination with a main cylinder and piston; of a steam supply from the boiler of the engine communicating with said cylinder to drive said piston; valve means for venting condensation from said cylinder, said valve means being urged toward closed position when steam pressure is present in said cylinder; and mechanism adapted to hold said valve means in venting position against pressure of steam in said cylinder, said mechanism having means operable by steam admitted thereto simultaneously with the admission of steam to said main cylinder to actuate said mechanism in a direction to permit closing of said valve means.

12. In a steam engine, the combination with a main cylinder; of valve means movable in one direction to vent said cylinder and in an opposite direction to close said cylinder against venting; a steam controlled element connected with said valve means, said element having a surface of pre-determined area adapted to be acted upon by steam to urge the valve means in one direction, and having a surface of greater area adapted to be subjected to steam pressure to urge said valve means in the opposite position; and independent means for controlling the admission of steam to said surfaces to regulate the position of said valve means.

13. In a steam engine including in combination a cylinder having a steam inlet; means for venting condensation from said cylinder, said means being urged to closed position when steam pressure is present in said cylinder; control means arranged to normally yieldably place said venting means in venting position against pressure in said cylinder; and additional means for exerting force upon said control means for overcoming the same to permit closing of said venting means under the influence of pressure in said cylinder.

In witness that I claim the foregoing I have hereunto subscribed my name this 31st day of July, 1924.

JOHN L. MOHUN.
